UNITED STATES PATENT OFFICE.

ANTON PEDERSEN, OF OAKLAND, CALIFORNIA.

BILLIARD TABLE.

Application filed January 31, 1921. Serial No. 441,349.

To all whom it may concern:

Be it known that I, ANTON PEDERSEN, a citizen of Denmark, residing at Oakland, in the county of Alameda and State of California, have invented new and useful Improvements in Billiard Tables, of which the following is a specification.

My invention relates to improvements in billiard tables of the pocket variety and particularly to the ball receptacles therefor.

An object of the invention is the provision of a billiard table ball receptacle provided with a plurality of discharge gullies, each provided with a discharge opening, for separating the balls played by two opposing players.

A further object is the provision of a gate on the receptacle operable for diverting the balls played into either of the discharge 20 gullies.

A still further object is the provision of sliding traps for each of the discharge openings of the discharge gullies.

A still further object is the provision of 25 levers operably jointed together for operatively opening one division of the traps while closing another division thereof when the gate is operatively swung from one position to the other.

With the foregoing and other objects and purposes in view which will appear as the description proceeds, my invention resides in the combination and arrangement of parts and in the details of construction herein- 35 after described and claimed, it being understood that changes in the precise embodiment of the invention herein disclosed can be made within the scope of what is claimed without departing from the spirit of the in- 40 vention.

In the accompanying drawings—

Figure 1 is a top view of a billiard table constructed in accordance with my invention, the top of the table being removed and 45 a portion of the frame broken away to better show the receiving receptacle.

Figure 2 is a sectional elevation of the table on line 2—2, Fig. 1.

Figure 3 is a plan view of the receiving 50 receptacle.

Figure 4 is a bottom view of the receiving receptacle.

Figure 5 is a cross section on line 5—5, Fig. 3.

55 Figure 6 is a longitudinal sectional view on line 6—6, Fig. 3.

Referring to the drawings in detail, throughout which like reference characters designate like parts—

The numeral 1 designates the side members, 2 the end members, 3, 4, frame braces and 5 the top, of a pocket billiard table of a well known design. The table is supported by the usual legs 6, and its top is provided with a cushioning bar 7.

About the margin of the table are the usual pockets, designated by the numeral 8, with which intersect the outer ends of inclined receiving gullies 9, which discharge into an inclined secondary gully 10.

To the lower side of one of the end members 2 is rigidly secured a receiving receptacle 11, which is provided upon its upper side with a pair of laterally spaced apart curved distributing channels 12, 12', which intersect at their inner ends and are united to the discharge end of the secondary gully 10.

Upon one side of the brace 3, and upon opposite sides of the brace 4, are rigidly secured brackets 14, 14', which support pivot pins 15, 15', which project rotatably through intermediate portions of primary levers 16, 16', to the upper ends of which are secured one end of extensible coil springs 17, 17', 80 which have their opposite ends connected to the rear end of the table, and primary wires 18, 18', which extend forwardly and are secured to handles 19, 19', which project slidably through the end member 2 at the front 90 end of the table.

To the lower ends of the primary levers 16, 16', are attached the inner ends of operating wires 20, 20', which have their outer ends attached to one end of traps 21, 21', 95 which are slidably disposed between the side walls of the receptacle 11 and longitudinally extending cleats 22, 22' secured to the bottom thereof. Upon one end of the receptacle 11 is secured a downwardly projecting 100 end piece 23, against the inner side of which the traps may be operatively moved.

Upon the lower side of the traps 21, 21', are downwardly projecting pins 24, 24', which are slidably disposed in slots 25, 25', 105 extending vertically through the outer ends of operating levers 26, 26', which have their intermediate portions pivotally supported by pivot pins 27, 27', secured to the lower sides of the cleats 22, 22'.

To the inner ends of the operating levers 26, 26', are pivotally connected one end

each of a pair of connecting levers 27^a, 27^b, the opposite ends of which are pivotally connected to the outer ends of a secondary lever 28, equi-distant from either end 5 of which is rigidly secured the lower end of a vertically extending pintle 29, which is disposed to rotate in a vertical opening 30 with its upper end rotatably supported by a bearing plate 31 secured to the upper 10 side of the receptacle 11.

32 designates a gate, which has one end rigidly secured to an intermediate portion of the pintle 29 and disposed to operatively swing in the channels 12, 12', at their point 15 of intersection with each other.

To operate my improved table (in describing which operation will consider the working parts of the table to be initially in a position as indicated in the accompanying drawings), assuming that the first 20 player has finished playing and the balls played by him have been deposited in the channel 12, the handle 19 is drawn out as far as it will go, which causes the upper end of the primary lever 16 to swing forwardly in a direction toward the handle named, against the tension of the spring 17, and the lower end of the lever to swing in the opposite or rearwardly direction thereby 25 causing the secondary wire 20 to be drawn rearwardly to slide the trap 21 in the same direction and away from its position over the lower end of the discharge opening 13. Said rearward movement of the 30 trap 21 causes the operating lever 26 to rotate about the axis of the pivot pin 27 and its inner end to swing rearwardly causing the connecting lever 27^a to move rearwardly and thereby rotate the secondary lever 28 to rotate the pintle 29 and swing the gate 32 away from the mouth of the channel 12' to open it for the reception of the balls played by the second player and to swing the gate into the mouth of the channel 12 against the passage of said balls thereinto, and opening the trap 21 for the discharge of the said balls played by the first 35 player from the channel 12. The arrangement of the secondary lever 28, connecting lever 27^b, operating lever 26' and primary lever 16', is such that the said drawing out 40 of the handle 19 and the movement of said first named set of levers and wires will

cause the second named set to move in operative opposite directions thereby closing 55 the trap 21' and drawing the handle 19' inwardly toward the member 2 as far as it can go.

I claim:

1. The combination with a billiard table 60 provided with a discharge gully, of a receiving receptacle rigidly secured to one end of the table and operatively connected to one end of the gully, the receptacle provided with a pair of laterally spaced apart discharge 65 channels, a gate operatively swingable from the mouth of one of said channels to the mouth of the other channel, the channels provided with discharge openings at their outer ends, traps for closing said openings, 70 and means connecting said traps with said gate, the arrangement being such that when said gate is operatively swung it will cause both of said traps to operatively move.

2. The combination with a billiard table 75 having a central secondary gully, of a receiving receptacle provided with a pair of laterally oppositely disposed distributing channels having their inner ends intersecting and connected to the discharge end of 80 said gully, the outer ends of said channels provided upon their lower sides with downwardly projecting openings, a pair of traps slidably secured to the receptacle for alternately closing said openings against the 85 passage therethrough of billiard balls projected operatively along said channels, and means operatively movable for alternately closing said openings.

3. In a billiard table of the character described, in combination, a receiving receptacle having a pair of laterally oppositely disposed distributing channels, a gate for alternately operatively closing the receiving 90 ends of said channels, a pair of traps for alternately operatively closing the discharging ends of the channels, and a connection between said traps and gate whereby the same may be operatively simultaneously moved.

In testimony of the foregoing being my own, I have hereunto affixed my signature this 25th day of January, 1921.

ANTON PEDERSEN.
